MOUTH ORGAN WITH FINGERING
SELECTOR

Joseph Lederfine, Brooklyn, N. Y.

Application September 13, 1947, Serial No. 773,861

6 Claims. (Cl. 84—377)

1

This invention relates to improvements in wind instruments in the nature of harmonicas, mouth organs and the like.

An object of the invention is to provide an improved form of mouth organ or harmonica in which the selection of the notes and chords to be played is accomplished by fingering rather than by the usual manner of cooperative movement of the mouth and tongue over selected air discharge and intake openings communicating with individual reeds.

Another object of the invention is to provide an improved form of mouth organ or harmonica including a hollow harmonica body having a reed plate disposed therein, one face of the reed plate being in communication with a mouthpiece common to all reeds, and having a plurality of finger holes in communication through individual ducts with the reeds on the other face of the reed plate, whereby, as air is caused to move into or out through said mouthpiece, only those reeds are actuated whose finger holes are unblocked by the fingers of the player.

A further object of the invention is to provide an improved form of mouth organ or harmonica including a pair of complementary body sections adapted to be joined along their opposed edges to form a hollow harmonica body, each body section being recessed to receive a portion of the edge of a reed plate disposed therebetween and thus dividing the interior chamber of the harmonica body into first and second compartments on opposite sides of the reed plate, the body sections having complementary extensions which when assembled define a mouthpiece communicating with said first compartment, the second compartment being subdivided into sub-compartments communicating between each pair of inhale-exhale reeds and a finger hole corresponding thereto and formed in the exterior wall of the second compartment.

Still another object of the invention is to provide an improved form of mouth organ or harmonica which is so arranged as to be easily mastered by a novice, without the necessity for an extensive and costly course of instruction therein.

A further object of the invention is to provide an improved and novel form of mouth organ or harmonica having the general external appearance in many respects similar to that of an ocarina, but which is in reality a reed instrument with individual interior reeds for each note.

Still another object of the invention is to provide a novel form of mouth organ which is simple in design, inexpensive to manufacture, and which is simple to use and provides good tonal quality.

Other objects and advantages of the invention

2

will become apparent from the following description of a preferred embodiment thereof as illustrated in the accompanying drawings, in which,

Figure 1 is a top plan view of my improved mouth organ,

Figure 2 is a sectional elevation taken on line 2—2 of Figure 1,

Figure 3 is a front elevational view of the instrument shown in Figure 1,

Figure 4 is a plan view taken on line 4—4 of Figure 3 and showing the bottom half of the mouth organ,

Figure 5 is a plan view taken on line 5—5 of Figure 3 and showing the upper half of the mouth organ, and

Figure 6 is a fragmentary sectional elevation taken on line 6—6 of Figure 3.

In the use of conventional types of harmonicas and mouth organs, it is necessary to learn a quite complicated system in which the mouth is moved along the entire length of the harmonica opposite the location of the particular notes to be played, and the tongue must be so disposed as to expose only the specific openings which communicate with the desired reeds. This manipulative technique is often a stumbling block to those who wish to learn how to play the harmonica, and frequently prevents them entirely from using this small, compact and companionable musical instrument.

The present invention makes it unnecessary to employ the mouth and tongue for locating the notes to be played, it being simply required that the player blow or draw upon the mouthpiece as needed, all location of the notes and chords being accomplished by means of the fingers. In order to understand clearly the nature of the invention and the best means for carrying it out, reference may now be had to the drawings, in which like numerals denote similar parts throughout the several views.

As shown, my improved mouth organ and harmonica includes a hollow housing or harmonica body generally indicated at 10, and formed of upper and lower complementary hollow portions 12 and 14 which may for convenience be termed upper and lower halves, although they may not necessarily divide the body 10 accurately in half. The lower body half 14 has a smoothly rounded external contour as shown, and the upper body half 12 is similarly rounded, so as to present no sharp or rough edges to the hand of the player and to comfortably fit his hand and mouth when in use. The harmonica body 10 may be formed of molded plastic material or other suitable substance.

Complementary upper and lower inner cham-

bers 16 and 18 are formed inside the upper and lower body halves 12 and 14 respectively, both chambers extending longitudinally throughout the length of the reed plate 20 which is disposed therebetween. The reed plate thus forms a partition wall effectively separating the chambers 16 and 18 from each other, being seated along its edges in recesses 22 and 24 formed along the abutting edges of the upper and lower body halves 12 and 14. Seating the reed plate in these recesses allows the abutting edges of the upper and lower halves 12 and 14 to come into mutual contact when assembled as in Figures 1, 2 and 3, the halves being preferably secured together along their abutting edges by cement or otherwise to form a tight seal, as at 26.

The upper inner chamber 16 is divided by a number of lateral upstanding inner walls or partitions 30, into individual upper inner compartments 32, the spacing between adjacent inner partitions 30 being such as to include therebetween one blow and one draw reed 34 and 36, corresponding to two adjacent notes in the musical scale covered by the harmonica. From Figure 5, it will be seen that each upper inner compartment 32 communicates with the outer atmosphere through an individual fingering hole 38 which is formed in the upper wall surface 40 of the upper body half 12.

The upper portions of the fingering holes 38 are divergently frusto-conical, as seen best in Figures 1 and 2, each being encircled by an upstanding annular rim 42 which is thus raised above the surface 40 of the upper body half 12, and is so proportioned as to allow the finger tip of the player to easily locate the same and to be placed thereon to block the fingering hole 38 when desired. There are eight such fingering holes 38, arranged as shown best in Figure 1, each fingering hole thus corresponding to a pair of reeds 34 and 36 in the reed plate and communicating with those reeds only, through the intervening upper inner compartment 32 corresponding therewith.

The reed plate 20, as shown in Figures 2 and 5, forms the floor of the upper inner chamber 16, being set along its four edges into the recess 22 so as to block passage of air past its edges or between adjacent inner compartments 32, the reed plate being cemented into the recess 22 and to the underlying outer edges of the partition walls 30 if needed for this purpose. From Figures 2 and 5, it will also be seen that the wall 44 is continued through the upper mouthpiece extension 46 which is integral with the upper half 12, to provide a continuous outer seat for the reed plate. The rest of the upper mouthpiece extension 46 is hollowed out as at 48, being open at 50.

The reed plate 20 is of a form well known in the art and commonly employed in conventional harmonicas, having a plurality of blow and draw reeds 34 and 36 overlying lateral slots 52 and secured at one end of the reed to one end portion of the slot by means of rivets 54, the reed being free to vibrate under the influence of an air stream passing through the slot in a direction tending to lift the reed and thus to slightly uncover the slot.

The lower body half 14 also has a mouthpiece extension portion 56 formed integrally therewith, having the same general contour as the upper mouthpiece extensions 46 and hollowed out as at 58 to form when combined with the upper recess 48, an entrance vestibule for the passage of air

as the player blows and draws upon the mouthpiece, the lower mouthpiece extension also being open at its left hand end as seen in Figure 2. It will be seen from Figure 2 that the wall 44 blocks entrance of air directly into the upper compartments 32, and that when the player blows upon the mouthpiece, air enters the mouthpiece vestibule, flowing in the direction of the arrows 60 into the lower chamber 18 and upwards through the reed plate slot 52, into the upper compartment 32, causing the reed 34 to vibrate and to produce a musical sound. The air leaves the upper compartment 32 through the finger hole 38 as seen in Figure 2.

It will be apparent that when the player blows on the mouthpiece, all the "blow" reeds 34 whose fingering holes 38 are uncovered will vibrate to produce musical sounds in accordance with their respective pitch. Accordingly, the player will cover with his finger tips, all the fingering holes 38 except those which correspond to the notes he desires to play. And similarly, when he inhales or draws upon the mouthpiece, all those reeds 36 will vibrate and make musical sounds except the reeds whose corresponding fingering holes 38 are covered with the fingers, the direction of the air upon inhaling being the reverse of that for blowing, and passing only through the uncovered holes 38 and the underlying draw slots to vibrate the "draw" reeds 36.

As is well known in the art, the direction of passage of the air in blowing will cause the "draw" reeds to close their slots 52 and the direction of the passage of the air in "drawing" will cause the "blow" reeds to close their slots 52. As shown in Figures 2 and 4, the lower chamber 18 is also divided by lateral partition walls 62 which are integral with the lower body half 14 and extend from the inner wall surface 64 to locations 66, allowing the air passing through the mouthpiece to flow upon blowing, in the direction of the arrows shown in Figure 4, and in the reverse direction upon "drawing." These lower partition walls 62 also provide support from below for the overlying reed plate 20, being directly below the upper partition walls 30. It will be noted that the reed plate has its ends extending partly across the kidney bean shaped end recesses of the upper and lower halves as shown in Figure 5.

These kidney bean shaped recesses 68 are formed in the end portions of the upper and lower body halves 12 and 14 in the molding process when they are made of plastic or other similar materials, and to aid in assembly, each lower half 14 has a cylindrical recess or socket 70 formed therein at each end to receive an upstanding locator pin 72 molded integrally with the abutting surface of the upper half 16, as shown in Figure 6.

From the foregoing description, it will be seen that the instrument described is quite simple in design, has only three major parts, namely the two halves and the reed plate, and is easily manufactured at low cost. The angularly inclined mouthpiece illustrated offers additional advantages among which are efficient wind distribution. It is also apparent that the instrument can be played quite easily, somewhat in the manner of the well known ocarina by blowing or drawing upon the mouthpiece and uncovering those finger holes corresponding to the notes to be played.

Although I have described a preferred embodiment of my invention in specific terms, it is to be understood that various changes may be made in

size, shape, materials and arrangement without departing from the spirit and scope of the invention as claimed.

I claim:

1. A mouth organ comprising a mouth organ body having a main chamber formed therein, a reed plate disposed in said chamber and dividing said chamber into upper and lower compartments, a mouthpiece formed integral with said body and communicating with said lower compartment, upper interior dividing walls spaced from each other and dividing said upper compartment into a plurality of upper sub-compartments isolated from each other and each opening inwardly upon a pair of inhale-exhale reeds in said reed plate, each of said upper sub-compartments having a fingering hole formed in its upper outer wall and constructed and arranged to form a seat to receive the finger tip of the player, so as to be normally closed thereby, whereby upon passage of air through said mouthpiece caused by suction or blowing upon said mouthpiece and the uncovering of any of said fingering holes, the corresponding reed in the path of said air is caused to vibrate to produce a musical sound, and a plurality of air-guiding partial partition walls formed integrally with the bottom and one wall of said lower compartment and extending incompletely toward the opposite wall of said lower compartment, whereby air is free to flow between said mouthpiece and through the space between said air-guiding partition walls and the said opposite wall of said lower compartment.

2. A mouth organ comprising an upper half having an upper compartment formed therein, and divided laterally into a plurality of upper sub-compartments, a reed plate closing said upper sub-compartments with each adjacent pair of inhale-exhale reeds in said plate communicating with one of said upper sub-compartments, and a lower half adapted to be joined to said upper half and having a lower compartment formed therein, whereby said reed plate separates said upper and lower compartments from each other, and a mouthpiece communicating with said lower compartment, each of said upper sub-compartments having a fingering hole formed in an upper outer wall thereof and adapted to be closed by the finger of the player, said fingering hole being constructed and arranged to direct air directly at said reeds in a path from the outside extending entirely at right angles to the plane of the reed plate.

3. A mouth organ comprising a hollow harmonica body, a reed plate disposed in said harmonica body and dividing the interior of the same into upper and lower major chambers, a mouthpiece communicating with said lower chamber, said upper chamber having a plurality of fingering holes formed in an upper outer wall thereof and facing said reed plate, and means for dividing said upper chamber into a plurality of compartmental ducts each communicating at one end with one of said holes and at its other end with a pair of inhale-exhale reeds in said reed plate.

4. A mouth organ comprising a hollow har-

monica body, a reed plate disposed in said harmonica body and dividing the interior of the same into upper and lower major chambers, a mouthpiece communicating with said lower chamber, upper inner partition walls dividing said upper chamber into a plurality of upper compartments and isolating within each compartment an inhale and an exhale reed of said reed plate, each compartment having a fingering hole formed in an outer wall thereof facing said reed plate and constructed and arranged to receive and to be normally closed by a finger of the player, whereby, as air is caused to flow through said mouthpiece by said player, only those reeds are actuated whose finger holes are unblocked by the fingers of the player.

5. A mouth organ comprising a hollow upper and a lower complementary body section adapted to be joined along their opposed edges to form a hollow harmonica body, each body section having a recess formed in said opposed edge, a reed plate seated in said opposed recesses and dividing the hollow interior of said harmonica body into upper and lower chambers on opposite sides of said reed plate, said body sections having complementary hollow extensions which when thus assembled form a mouthpiece communicating with said lower chamber and the underside of said reed plate and thus being common to all reeds, a plurality of fingering holes providing finger tip seats formed in an outer upper wall of said upper chamber facing said reed plate, the number of said holes being equal to one half the total number of reeds in said reed plate, the said upper chamber being subdivided by lateral walls into a plurality of sub-compartments communicating between each pair of adjacent inhale-exhale reeds and one of said fingering holes and isolating each said pair of reeds from other pairs of reeds.

6. The construction according to claim 5, characterized further in that said lower chamber is provided with a plurality of partial partition walls corresponding in number and relative positions to the lateral walls in said upper chamber and dividing said lower chamber into a plurality of recesses open at one end and communicating at their said open ends with said mouthpiece, whereby the flow of air is guided.
